UNITED STATES PATENT OFFICE.

JAMES T. HALSEY, OF RICHMOND, VIRGINIA.

VALVE-GEAR.

SPECIFICATION forming part of Letters Patent No. 294,873, dated March 11, 1884.

Application filed October 5, 1883. (No model.)

To all whom it may concern:

Be it known that I, JAMES T. HALSEY, of Richmond, in the State of Virginia, have invented a new and useful Improvement in 5 Valve-Gears for Steam and other Engines, of which the following is a specification.

My invention relates to that class of engines in which the motive fluid is admitted to the opposite ends of the main cylinder through 10 ports governed by a main valve, and in which the main valve is provided with suitable inlets or passages controlled by a secondary or cut-off valve, which slides upon said main valve, the object of my invention being the 15 provision of improved devices for imparting motion to the valves.

In the accompanying drawings, which represent a preferred form of a convenient embodiment of my invention, Figure 1 is a side elevation representing my improvements. 20 Fig. 2 is a top plan view of the same, and Fig. 3 a transverse sectional elevational detail.

Similar letters of reference indicate corresponding parts.

25 In the drawings, A represents the eccentric-shaft, upon which is mounted the eccentric B, the connection being rigid and effected in the usual manner.

30 C is the eccentric-yoke which encircles the eccentric, and through the medium of which motion is imparted to the valve-stems.

D is the valve-stem of the cut-off valve, and 35 E the valve-stem of the main valve. The valve-stem of the cut-off valve is connected with the eccentric-yoke by means of the pivot F, which is directly attached to said yoke. The valve-stem of the main valve is connected with an upright lug, g, being a part of or connected with a slide, G, which latter is pivotally connected with the eccentric-yoke by 40 means of the pivot H, and is conformed to reciprocate upon a fixed way, I, connected with the bed-frame J of the engine. The connection of the slide with the fixed way upon which 45 it travels is represented as that of a dovetailed tongue and groove, as is clearly shown in Fig. 3. Other analogous connections may, how-

ever, be substituted in the stead of the above-named tongue and groove.

The valve-stems D and E are connected 50 with the valves in the usual manner, a description of which latter would be redundant in this specification.

Such being a description of a convenient embodiment of my invention, its operation 55 takes place upon the actuation of the eccentric by its shaft, occasioning the actuation of the yoke and consequently of the valve-stems, the valve-stem of the main valve operating through the intermediate instrumentality of the slide, 60 the object of which latter is to guide the motion of said stem and to steady the throw of the eccentric-yoke. The position of the pivot F considered with respect to the pivot H is such that a line through the center of the two 65 pivots would be perpendicular to a line passing through the center of the eccentric and a point central between the centers of the pivots aforesaid.

Incident to the above invention is the advantage that the motion of the cut-off valve is caused to be most rapid when the main valve is at the end of its travel, so that the valves can be opened wide enough to give the motive fluid a free entrance and can then be closed 75 with a quick motion as early or late in the stroke as may be found desirable.

Having thus described my invention, I claim and desire to secure by Letters Patent—

1. The combination, in a valve-gear, of the 80 eccentric, eccentric-yoke, valve-stem of the cut-off valve, valve-stem of the main valve, slide, and way for the slide, the arrangement and connection of the parts being such substantially as is set forth.

2. The combination, in a valve-gear, of the 85 eccentric-yoke provided with a pivot, F, with the slide G.

In testimony whereof I have hereunto signed my name this 14th day of July, A. D. 1883.

JAMES T. HALSEY.

In presence of—

J. BONSALL TAYLOR,
JOHN JOLLEY, Jr.
